UNITED STATES PATENT OFFICE.

RICHARD MANSLEY, OF PHILADELPHIA, PENNSYLVANIA.

IMPROVEMENT IN HEMP-BRAKES.

Specification forming part of Letters Patent No. **22,661**, dated January 18, 1859.

To all whom it may concern.

Be it known that I, RICHARD MANSLEY, of the city and county of Philadelphia, and State of Pennsylvania, have invented a new and useful Improvement in Hemp-Brakes; and I do hereby declare the following to be a full, clear, and exact description of the same, reference being had to the accompanying drawings, and to the letters of reference marked thereon.

My invention relates to an improvement in that class of hemp-brakes in which horizontal slides with transverse bars are used in connection with stationary bars; and my improvement consists in operating the slide by means of an arm, cam, and spring arranged substantially as described hereinafter, the spring being so graduated that when the slide has been impelled to the limit of its outward movement it shall instantly recede, thereby effectually opening the fibers and shattering the ligneous pith of the hemp.

In order to enable others to make and use my invention, I will now proceed to describe its construction and operation.

On reference to the accompanying drawings, which form a part of this specification, Figures 1 and 2 are sectional elevations of my improved hemp-brake; Fig. 3, a transverse section.

A is the foundation of the machine, to which are secured the three vertical posts B, additional steadiness being imparted to the latter by the diagonal braces C, and the posts being connected together at the top by the transverse piece d.

In the spaces between and near the top of the posts are firmly secured a series of horizontal bars, e e, with beveled edges. These bars are a sufficient distance apart to admit without contact the beveled edges of another series of bars, f f, a set of which is secured to the end of each of the slides D and D', which are arranged to move horizontally in guides attached to the intermediate posts, E, and rear posts, F, which are firmly secured to the base A. Each of the slides D and D' has a cross-bar, h, which has an opening, for the admission of the end of the long arm of the lever G, secured to a shaft, i, which is arranged to vibrate in attachments to the intermediate posts, E. A shaft, g, turns in the same attachments, and to this shaft are secured two cams, H and H'—one

for acting on the lever G of one slide and the other for acting on the lever of the other slide. The short arm of each lever is connected by a rod, I, to a spring, J, secured to the transverse bar which connects together the tops of the rear uprights, F. A shoulder, m, is formed on the short arm of each lever, so that as the cam revolves the rounded edge bears against the edge of the lever above the shoulder and moves it, with the slide, to the position shown in Fig. 1 when the bars f are at the limit of their backward movement. As the cam continues to revolve, however, its point passes the shoulder m of the lever, which, through the action of the spring J, suddenly moves to the position shown in Fig. 2, and carries the slide forward so far that the beveled edges of the bars f enter a short distance into the spaces between the stationary bars e e. This position of the slide, however, is but of momentary duration, for the spring J is so graduated that the moment the slide has been projected forward to the extent described it recedes to a slight extent and remains stationary, its bars f a short distance from the stationary bars e, until the cam again moves the slide back to the position shown in Fig. 1. It will thus be seen that as the shaft revolves the slides will be drawn back by a gradual motion and projected forward by a sudden impulse, the last portion of the forward movement being effected through the momentum of the slide, acquired by the action of the spring in the first instance, and not by the direct action of the spring throughout; hence the sudden receding of the slide prior to its being drawn back by the cam. The attendant stands on the platform j in front of the machine, and, holding in his hands a bundle of hemp-stalks, passes it between the stationary bars e and movable bars f. By the repeated blows of the latter the pith or ligneous matter is broken and the fibers are split open, so as to allow this ligneous matter to escape onto the inclined platform k, down which it slides to the ground.

I have found by practical experiment that the ligneous pith of hemp is more effectually shattered and the fibers more readily opened by a sudden blow than by a gradual pushing movement, such as is attained in many hemp-brakes by a crank motion. In order to render the sudden blow most effective, it is important

that the bars should not remain pressed against the hemp after the blow is struck, but should instantly recoil, as described above.

I do not claim, broadly, the employment, in hemp-brakes, of horizontally-moving slides, with bars so situated that the hemp may be presented vertically to the machine, as such a device has been heretofore used; but

I claim and desire to secure by Letters Patent—

Operating the horizontal slides D, with its transverse bars, by the cam H, arm G, and

spring J, when arranged substantially as described, and when the said spring is so graduated that the slide shall instantly recede after reaching the limit of its outward movement, as and for the purpose herein set forth.

In testimony whereof I have signed my name to this specification in the presence of two subscribing witnesses.

RICHARD MANSLEY.
